SASH OR STORE FRONT CONSTRUCTION

Clyde D. Lowry, Toledo, Ohio, assignor to Libbey-
Owens-Ford Glass Company, Toledo, Ohio, a
corporation of Ohio

Application October 14, 1937, Serial No. 168,934

12 Claims. (Cl. 189—69)

This invention relates broadly to store or window fronts and more particularly to the provision of an improved ventilator construction.

Among the objects of the invention are the provision of a hinged ventilator of maximum simplicity, efficiency, and ease of assembly; which is of strong, sturdy and durable construction; which may be readily opened and closed; and which is provided with means for sealing it against the entrance of water, dirt, etc.

Other objects and advantages of the invention will become more apparent during the course of the following description when taken in connection with the accompanying drawing.

In the drawing wherein like numerals are employed to designate like parts throughout the same:

Fig. 1 is a face view of a portion of a ventilator provided by the invention; and

Fig. 2 is a vertical section therethrough.

Referring more particularly to the disclosure in the accompanying drawing, the window frame in which the improved ventilator is adapted to be mounted consists of the horizontal sill A, horizontal head jamb B, and opposite vertical side jambs C, only one of which is shown. Arranged within the window frame is the metal sash construction for carrying the ventilator and including the sash sections 5, 6 and 7 mounted respectively upon the sill A, head jamb B, and side jambs C.

Each metal sash section 5, 6 and 7 comprises a stationary back member 8 and a movable front member or face piece 9. The back member 8 comprises a vertical rear wall 10 which abuts and is secured to a back stop 11 extending around the window frame by wood screws 12. Formed integral with the rear wall 10 adjacent its upper end is an inwardly directed gutter portion 13 terminating in a substantially vertical lip 14. The rear wall 10 is provided at its lower end with a supporting foot 15 which engages the respective sill or jamb and extending forwardly from said foot is a horizontal ledge 16 having formed integral therewith, adjacent its outer end, a base flange 17 in horizontal alignment with the foot 15 and also engaging the respective sill or jamb. The outer end 18 of the ledge 16 cooperates with the base flange 17 to form a substantially U-shaped channel for receiving the turned lower end 19 of the front member 9, said front member being provided at its upper end with a lip 20 disposed opposite the lip 14 on back member 8. The adjacent ends of the sash sections 5, 6 and 7 are

mitered at the corners of the window frame as indicated at 21.

Carried by the front member 9 of each sash section are a plurality of spring arms 22 secured at their upper ends in a groove 23 formed in said front member, while carried at the lower end of each spring arm is a lever member 24 from which extends a substantially horizontal lever arm 25. The lever member 24 is provided with a series of teeth 26 adapted for engagement with the toothed or rack portion 27 formed on the upper surface of the ledge 16. The tensioning or adjusting means comprises a plurality of set screws 28 threaded through the gutter portion 13 of the back member 8 and adapted to engage the outer ends of the lever arms 25. The rocking movement of the lever arms 25 by the adjusting screws 28 is limited by a positive stop member 29 also carried by the back member 8.

Carried by the metal sash sections 5, 6 and 7 are the relatively wide molding strips 30, 31 and 32 respectively, which strips cooperate to form a substantially rectangular frame within which the ventilator, designated in its entirety by the numeral 33, is received. The molding strips 30, 31 and 32 are mitered at their adjacent ends as indicated at 34 and the inner longitudinal marginal portion 35 of each molding strip is received between the lips 14 and 20 of the back and front members 8 and 9 of the respective sash section 30, 31 or 32, being firmly clamped therebetween upon tensioning of the screws 28. Each molding strip 30, 31 and 32 is also provided with a forwardly directed horizontal shoulder 36 which is adapted to engage the upper end of the front member 9 of the respective sash section to effect the proper positioning of the molding strip with respect to said sash section.

To install the molding strips 30, 31 and 32, the back members 8 of the sash sections 5, 6 and 7 are first properly secured in place by the screws 12 to the sill A, head jamb B, and side jambs C. The front members 9 of the sash sections, equipped with the desired number of spring arms 22 and lever members 24, are then moved into position by placing the lower or outer end 19 of each front member under the outer end 18 of the ledge 16 of the back member and shoving the same rearwardly to bring the lip 20 into engagement with the front face of the respective molding strips 30, 31 and 32 and the inner face of said molding strip into contact with the lip 14 of the back member.

When the parts are assembled in this manner, the teeth 26 of the lever members 24 will engage

the toothed or rack portion 27 on the ledge 16 and during this installation, the tensioning screws 28 are all in retracted position so that they will not interfere with proper assembling of the parts. 5 To then secure the molding strips in position, the tensioning screws 28 are adapted to be tightened down to the maximum limit possible which is determined by engagement of the lever arms 25 with the stop 29, said stop acting to prevent 10 excessive tensioning of the screws. During the tightening of the screws 28, the lever arms 25 will be forced downwardly so that the lever members 24 will rock upon the toothed portion 27 on the ledge 16 and as the teeth 26 of said lever members 15 are in engagement with said toothed portion, movement of the lever arms results in a bending or flexing of the spring arms 22, and it is this spring tension which clamps the molding strip between the front and back members of 20 the metal sash. The particular type of metal sash sections 5, 6 and 7 herein disclosed form no part of the present invention per se as they are more specifically illustrated, described and 25 claimed in my Patent No. 2,103,732, issued Dec. 28, 1937.

The ventilator 33 comprises a rectangular main frame 37 comprising horizontal bottom and top members 38 and 39 and vertical side members 40 suitably connected together and mitered at their 30 adjacent ends as at 41. Each frame member 38, 39 and 40 is provided at its forward edge with an inwardly directed flange 42 which engages the outer face of the glass sheet 43 inserted within 35 said frame. Mounted within the main frame 37, inwardly of glass sheet 43, is a sub-frame composed of strips 44 L-shaped in cross section and having flanges 45 engaging the inner face of the glass sheet. The flanges 42 and 45 serve to firmly 40 secure the glass sheet within the frame 37, although the said sheet can be readily removed by simply removing the screws 46 which secure the strips 44 in place. The members 38, 39 and 40 of the main frame 37 are each provided intermediate 45 its inner and outer edges with an outwardly extending, substantially wide rib 47, said ribs being disposed inwardly of and overlapping the molding strips 30, 31 and 32.

The main frame 37, carrying the glass sheet 43, is adapted to be hinged to one of the molding 50 strips 30, 31 and 32 and, as shown in the drawing, the said frame is attached to the molding strip 30 by means of a hinge 48, one section of the hinge being secured to the said molding strip 30 by screws 49 while the other hinge section is secured to the rib 47 of frame member 38 by screws 55 55. When the ventilator 33 is moved to closed position as shown in full lines in Fig. 2, the main frame 37 will be received within the window opening defined by the molding strips 30, 31 and 32, 60 with the front faces of said molding strips being substantially flush with the flanges 42 which form the front face of the ventilator frame 37. On the other hand, when the ventilator is opened, the upper end thereof is swung inwardly upon 65 hinges 48 as indicated by the broken lines in Fig. 2 and any suitable means can be provided for holding the ventilator in the desired open position.

In order to effectively seal the ventilator against the entrance of dirt, water, etc., there is carried 70 by the rib 47 of each frame member 38, 39 and 40, a longitudinally extending strip 51 of rubber, rubber composition, or the like, and which strips engage the inner faces of the molding strips 30, 31 and 32 to form a tight joint when the ventilator is in closed position.

It is to be understood that the form of the invention herewith shown and described is to be taken as the preferred embodiment of the same, and that various changes in the shape, size and arrangement of parts may be resorted to without departing from the spirit of the invention or the scope of the subjoined claims. 5

I claim:

1. In a sash or store front construction, the combination with a window frame, and a metal sash construction extending around said frame and carried thereby, of molding strips removably carried by the metal sash construction and defining a window opening, and a ventilator for closing said window opening hinged to one of said molding strips and removable therewith without requiring disassembly of the metal sash construction, said ventilator engaging another of said molding strips when in closed position. 15

2. In a sash or store front construction, the combination with a window frame, and a metal sash construction extending around said frame and carried thereby, of molding strips removably carried by the metal sash construction and defining a window opening, a ventilator for closing 25 said window opening hinged to one of said molding strips and removable therewith without requiring disassembly of the metal sash construction, said ventilator engaging another of said molding strips when in closed position, and means 30 for sealing the ventilator when closed against the entrance of dirt and water. 35

3. In a sash or store front construction, the combination with a window frame, and a metal sash construction extending around said frame and carried thereby, said sash construction including relatively movable front and back members, of molding strips removably clamped between the front and back members of the metal sash construction and defining a window opening, 40 and a ventilator for closing said window opening hinged to one of said molding strips and removable therewith without requiring disassembly of the metal sash construction, said ventilator engaging another of said molding strips when in 45 closed position.

4. In a sash or store front construction, the combination with a window frame, and a metal sash construction extending around said frame and carried thereby, said sash construction including relatively movable front and back members, of molding strips removably clamped between the front and back members of the metal sash construction and defining a window opening, a ventilator for closing said window opening hinged to one of said molding strips and removable therewith without requiring disassembly 50 of the metal sash construction, said ventilator engaging another of said molding strips when in closed position, and means for sealing the ventilator when closed against the entrance of dirt and water. 55

5. In a sash or store front construction, the combination with a window frame, and a metal sash construction extending around said frame and carried thereby, of molding strips removably carried by the metal sash construction and defining a window opening, and a ventilator for closing said window opening including a frame arranged inwardly of and hinged to one of said molding strips and removable therewith without requiring disassembly of the metal sash construction, said ventilator frame engaging another of said molding strips when in closed position. 65

6. In a sash or store front construction, the 75

combination with a window frame, and a metal sash construction extending around said frame and carried thereby, of molding strips removably carried by the metal sash construction and defining a window opening, a ventilator for closing said window opening including a frame arranged inwardly of and hinged to one of said molding strips and removable therewith without requiring disassembly of the metal sash construction, 5 said ventilator frame engaging another of said molding strips when in closed position, and means carried by the ventilator frame and engaging the molding strips for sealing the ventilator when closed against the entrance of dirt and water.

7. In a sash or store front construction, the combination with a window frame, and a metal sash construction extending around said frame and carried thereby, said sash construction including relatively movable front and back members, of molding strips removably clamped between the front and back members of the metal sash construction and defining a window opening, and a ventilator for closing said window opening including a frame arranged inwardly of and hinged to one of said molding strips and removable therewith without requiring disassembly of the metal sash construction, said ventilator frame engaging another of said molding strips when in closed position.

8. In a sash or store front construction, the combination with a window frame, and a metal sash construction extending around said frame and carried thereby, said sash construction including relatively movable front and back members, of molding strips removably clamped between the front and back members of the metal sash construction and defining a window opening, a ventilator for closing said window opening including a frame arranged inwardly of and hinged to one of said molding strips and removable therewith without requiring disassembly of the metal sash construction, said ventilator frame engaging another of said molding strips when in closed position, and means carried by the ventilator frame and engaging the molding strips for sealing the ventilator when closed against the entrance of dirt and water.

9. In a sash or store front construction, the combination with a window frame, and a metal sash construction extending around said frame and carried thereby, of molding strips removably carried by the metal sash construction and defining a window opening, a ventilator for closing said window opening including a frame comprising bottom, top and side members provided with outwardly projecting ribs arranged inwardly of and overlapping said molding strips, and hinge means for connecting the rib of one of said frame members to one of the said molding strips so that the said frame is removable with said molding strips without requiring disassembly of the metal sash construction.

10. In a sash or store front construction, the combination with a window frame, and a metal sash construction extending around said frame and carried thereby, of molding strips removably

carried by the metal sash construction and defining a window opening, a ventilator for closing said window opening including a frame comprising bottom, top and side members provided with outwardly projecting ribs arranged inwardly of and overlapping said molding strips, hinge means for connecting the rib of one of said frame members to one of the said molding strips so that the said frame is removable with said molding strips without requiring disassembly of the metal sash construction, and means carried by said ribs and engaging said molding strips for sealing the ventilator when closed against the entrance of dirt and water.

11. In a sash or store front construction, the combination with a window frame, and a metal sash construction extending around said frame and carried thereby, said sash construction including relatively movable front and back members, of molding strips removably received between the front and back members of the metal sash construction and defining a window opening, means independent of said molding strips for connecting the front and back sash members together to clamp said molding strips therebetween, said molding strips having shoulders engaging the front members of the metal sash construction to position the said strips with respect to the said metal sash construction, a ventilator for closing said window opening including a frame comprising bottom, top and side members provided with outwardly projecting ribs arranged inwardly of and overlapping said molding strips, and hinge means for connecting the rib of one of said frame members to one of the said molding strips so that the said frame is removable with said molding strips without requiring disassembly of the metal sash construction.

12. In a sash or store front construction, the combination with a window frame, and a metal sash construction extending around said frame and carried thereby, said sash construction including relatively movable front and back members, of molding strips removably received between the front and back members of the metal sash construction and defining a window opening, means independent of said molding strips for connecting the front and back sash members together to clamp said molding strips therebetween, said molding strips having shoulders engaging the front members of the metal sash construction to position the said strips with respect to the said metal sash construction, a ventilator for closing said window opening including a frame comprising bottom, top and side members provided with outwardly projecting ribs arranged inwardly of and overlapping said molding strips, hinge means for connecting the rib of one of said frame members to one of the said molding strips so that the said frame is removable with said molding strips without requiring disassembly of the metal sash construction, and means carried by said ribs and engaging said molding strips for sealing the ventilator when closed against the entrance of dirt and water.

CLYDE D. LOWRY.
